(57) CLAIM

The ornamental design for a dome playhouse, as shown and described.

DESCRIPTION

The present application is related to U.S. Pat. No. D286,307, issued Jul. 3, 1984, for Play House, by Joseph C. Roy, included by reference herein.

The present application is related to U.S. Pat. No. D302,836, issued Aug. 15, 1989, for Play House, by Joseph C. Roy, included by reference herein.

The present application is related to U.S. Pat. No. D351,637, issued Oct. 18, 1994, for Children's Playhouse, by Daniel A. Neiding, included by reference herein.

The present application is related to U.S. Pat. No. D501,232, issued Jan. 25, 2005, for Playhouse, by John C. Kirk, included by reference herein.

The present application is related to U.S. Pat. No. D533,605, issued Dec. 12, 2006, for Playhouse, by Oleksandr Krylevets, included by reference herein.

The present application is related to U.S. Pat. No. D569,450, issued May 20, 2008, for Play House by Glen H. Halliday, Jeffery L. Leighton, included by reference herein.

The present application is related to U.S. Pat. No. D594,070, issued Jun. 9, 2009, for Children's Playhouse, by Ray Dale Ridens, included by reference herein.

FIG. 1 is a top, front, and right side perspective view of a dome playhouse showing my new design;

FIG. 2 is a top, right side, and rear perspective view thereof;

FIG. 3 is a front elevational view thereof;

FIG. 4 is a right side elevational view thereof, the left side elevational view being a mirror image thereof;

FIG. 5 is a rear elevational view thereof; and,

FIG. 6 is a top plan view thereof, the bottom plan view being only one flat plane.
